Primary Examiner — Cynthia Ramirez*Assistant Examiner* — Tamara L Hahn(74) *Attorney, Agent, or Firm* — Heslin Rothenberg Farley & Mesiti P.C.(57) **CLAIM**

The ornamental design for a cart as shown and described.

DESCRIPTION

FIG. 1 is a front elevational view of a cart comprising the new design;

FIG. 2 is a top, back perspective view of the design of FIG. 1; and

FIG. 3 is a right side elevational view of the design of FIG. 1;

FIG. 4 is a bottom view of the design of FIG. 1;

FIG. 5 is top view of the design of FIG. 1;

FIG. 6 is a left side elevational view of the design of FIG. 1; and,

FIG. 7 is a back elevational view of the design of FIG. 1. The broken lines in the drawings depict portions of the cart that form no part of the claimed design.

1 Claim, 7 Drawing Sheets(56)
